UNITED STATES PATENT OFFICE.

JOHN WEIR, OF SCOTSTOWN, SCOTLAND, ASSIGNOR OF ONE-HALF TO ARCHIBALD NICOL LOW, OF PATRICK, SCOTLAND.

HATCHWAY-COVER.

1,013,912.

Specification of Letters Patent.

Patented Jan. 9, 1912.

Application filed May 3, 1911. Serial No. 624,732.

To all whom it may concern:

Be it known that I, JOHN WEIR, of 34 Norse road, Scotstown, Renfrewshire, Scotland, ship surveyor, have invented certain new and useful Improvements in and Connected with Hatchway-Covers, of which the following is a specification.

This invention relates to improvements in flexible hatchway covers composed of thin connected metal plates and adapted to be coiled upon drums, and consists in the particular form of the component plates and has for its object to expedite the putting on and removal of same, and making the hatchways rain tight.

In carrying out my invention, I construct the covers of laths or strips of metal held together by the abutting edges locking one with the other, and which run in suitable grooves in the sides of the hatch-way. Mov- able supports or stays for the cover are pro- vided immediately underneath the same. The cover is operated by any suitable gear- ing.

In order that my invention may be prop- erly understood and readily carried into effect, I have hereunto appended one sheet of drawings of which—

Figure 1 is a longitudinal section show- 30 ing the hatchway cover embodying my invention entirely drawn over the hatchway. Fig. 2 is a plan of the same showing the hatchway cover almost entirely drawn over the hatches. Fig. 3 is a longitudinal section 35 of the cover. Fig. 4 is a similar view illustrating a modification of the same all here- after more fully referred to and described.

With reference to the drawings, the hatch- way cover indicated by A is composed, in 40 one of its simplest forms, of thin metal plates or strips held together by bending up the abutting edges into the formation of hooks as seen in cross section, one plate or strip A¹ interlocking with its adjacent plate 45 or strip A² as seen more particularly in Fig. 3. This characteristic in construction per- mits of the cover A being coiled upon the drum or barrel B mounted as shown in the left hand side of the hatchway C, when it

is desired to give access to the hatch; the 50 cover is unwound and drawn by the ring D over the hatch-way in order to constitute a cover, as seen in Figs. 1 and 2. Guides E, F, are connected at both sides of the cover, and these embrace the bead or guides c¹ of 55 the hatchway C. The cover is also support- ed on a longitudinal guide or bar G. The drum or barrel may be rotated by a crank handle fitted upon the square H and H¹ of the spindle or by any other means. It will 60 be seen that the inclosing wall C¹ of the hatchway C, is divided by a partition C² so as to form a compartment for the roller. The partition C² extends toward but not to 65 the top of the inclosing wall and the guide C³ is mounted on the partition wall C² to properly guide the cover.

With reference to Fig. 4, the cover A is composed of duplex plates A³ and A⁴ one above and the other below and interlocking 70 together as shown.

Claim.

In combination with a vertical hatchway inclosing wall opening upwardly and hav- 75 ing a substantially horizontal upper margin provided with bead-like guides extending therefrom, a partition wall dividing said inclosing wall into a roller compartment and hatchway proper and extending toward but not to the top of said inclosing wall, a roller 80 in said compartment disposed below the upper edge of said partition wall, a cover guide on said partition, a horizontal cover guide bar extending across the hatchway proper and attached to said partition and 85 said inclosing wall, a jointed cover adapted to be wound off from said roller over said guide bar and fitting inside of the inclosing wall to close the hatchway, and guides on the end of said cover embracing the feet- 90 like extensions on the exterior of said inclos- ing wall.

In testimony whereof I affix my signa- ture in presence of two witnesses.

JOHN WEIR.

Witnesses:

JOHN LIDDLE,
JOHN TRAIN LIDDLE.

Correction in Letters Patent No. 1,013,912.

It is hereby certified that the residence of the assignee in Letters Patent No. 1,013,912, granted January 9, 1912, upon the application of John Weir, of Scotstown, Scotland, for an improvement in "Hatchway-Covers," was erroneously written and printed "Patrick, Scotland," whereas said residence should have been written and printed *Partick, Scotland*; and that the said Letters Patent should be read with this correction therein that the same may conform to the record of the case in the Patent Office.

Signed and sealed this 2nd day of April, A. D., 1912.

[SEAL.]

C. C. BILLINGS,
Acting Commissioner of Patents.
